United States Patent Office.

JAMES F. DUFFY AND WILLIAM P. FRAILEY, OF CHICAGO, ILLINOIS, SAID FRAILEY ASSIGNS HIS RIGHT TO SAID DUFFY.

Letters Patent No. 103,030, dated May, 17, 1870; antedated May 7, 1870.

IMPROVED SPRING BED-BOTTOM.

The Schedule referred to in these Letters Patent and making part of the same.

To all whom it may concern:

Be it known that we, JAMES F. DUFFY and WILLIAM P. FRAILEY, of Chicago, in the county of Cook and State of Illinois, have invented a new and useful Improvement in Spring Bed-Bottoms; and we do hereby declare that the following is a full, clear, and exact description thereof, which will enable others skilled in the art to make and use the same, reference being had to the accompanying drawings forming part of this specification.

This invention relates to a new and useful improvement in bed-bottoms, whereby they are made elastic and durable, and so that their several parts may be easily taken apart for transportation and repairs; and

The invention consists in construction and arrangement of parts, as hereinafter more fully described.

In the accompanying drawing—

Figure 1 is a top or plan view.

Figure 2 is a longitudinal section through the line *x x* of fig. 1.

Figure 3 is a view of a spring detached.

Similar letters of reference indicate corresponding parts.

A A represent frames, made of hoop-iron, consisting of longitudinal and transverse pieces crossing each other at right angles, and riveted together, as seen in the drawing.

In form and size these frames are made to correspond with the bedstead on which they are used.

Between these frames, the springs B are placed, more or less in number, and arranged in any manner to best sustain the weight upon them.

These springs are connected with the frames, so as to be readily detached therefrom.

The frames are provided with buttons at each point of connection with the springs, and the springs are provided with button-holes, in the form of key-holes, which allow the heads or buttons to pass through the round orifices, while the slots extending therefrom receive the necks of the buttons, which, while it secures the springs in place, allows them to be readily detached.

The form of the springs is seen in fig. 2. They are connected to the upper frame A at the upper curve by the buttons C.

The ends of the spring approach each other on the bottom frame, where they are connected at each end by buttons E.

In fig. 3 the spring is turned so as to show the form of the button-holes therein.

This bed-bottom is made in sections. F is the middle or body section, and G and H represent the head and foot sections. These sections are connected with the middle section by means of the button and button-hole fastening already described.

The central section is supported by an upper and a lower wooden frame, I J, which are secured to the parts or frames forming the section by means of screws. These wooden frames keep the iron frame and the middle section in place, and serve to properly distribute the pressure on the springs of that section.

K represents stays or rods, which connect the upper and the lower frames of the middle section. These stays cross each other, as seen in fig. 2, at each side. They are attached by means of the screws which connect the wooden frames, as seen in the drawing, and serve to prevent lateral motion. They are designed to be sufficiently elastic to allow compression of the springs B.

The springs B are made of a single piece of metal, with short curves L at the extremities of each, as seen. These small curves extend outward from the circumference of the spring circles or curve at the points most distant from the points of connection with the frame, and add greatly to the strength and elasticity of the springs.

The advantages of this mode of construction are, it makes a very strong bed-bottom and the sustaining power is properly distributed throughout, making it in sections, and so as to be readily taken apart, which is a great advantage in shipping and transportation.

Having thus described our invention,

We claim as new and desire to secure by Letters Patent—

1. The combination of the springs B and sections F G H, when constructed and arranged as shown and described, whereby the several parts are adapted to be detached from each other, for the purpose specified.

2. In combination with a spring bed-bottom, the springs B, when provided with the curves L and with key-hole slots to receive the buttons C E, as shown and described.

JAMES F. DUFFY.
WILLIAM P. FRAILEY.
